UNITED STATES PATENT OFFICE.

WILLIAM C. ACHTERKIRCH, OF OGILVIE, AND ERNEST B. MARSH, OF ANOKA,
MINNESOTA.

BULLETIN BOARD.

Application filed August 23, 1924. Serial No. 734,718.

To all whom it may concern:

Be it known that we, WILLIAM C. ACHTERKIRCH and ERNEST B. MARSH, citizens of the United States, residing at Ogilvie and 5 Anoka, respectively, in the counties of Kananbec and Anoka, respectively, and State of Minnesota, have invented certain new and useful Improvements in Bulletin Boards, of which the following is a specification, reference being had to the accompanying drawings.

This invention relates to bulletin boards and has for an important object thereof an improvement of the structure shown in the 15 prior patent of William C. Achterkirch, #1,252,640, issued January 8, 1918.

The primary objects of the present invention are to reduce the cost of construction of the bulletin board illustrated in said patent, 20 to produce a device of this character which may be very readily and durably constructed and which is not liable to be damaged by handling on the part of inquisitive inspectors.

25 A further object of the invention is to provide a device of this character which may be readily altered so as to increase or decrease the number of holding fingers which are employed thereon.

30 These and other objects we attain by the construction shown in the accompanying drawings, wherein for the purpose of illustration is shown a preferred embodiment of our invention and wherein:—

35 Figure 1 is a front elevation of a bulletin board constructed in accordance with our invention;

Figure 2 is a vertical sectional view therethrough;

40 Figure 3 is a section on the line 3—3 of Figure 2;

Figure 4 is a section on the line 4—4 of Figure 1;

45 Figure 5 is a perspective of the lower end of the retaining arm showing the sliding latch.

Referring now more particularly to the drawings, the bulletin board includes a rectangular frame 10, a back 11 for the frame, 50 and a plurality of arms 12 maintaining the matter to be exhibited in position upon the frame. The rectangular frame 10 consists of a top 13 and bottom 14 and connecting side members 15. The structure of the top member 13 and bottom member 14 will here-

inafter be more fully described. The side members 15 may be of any desired construction, although they are preferably constructed so that they resemble, in appearance at least, the top and bottom of the frame. 60

The top member 13 of the frame is formed from sheet metal formed to provide a front face 16 which is offset adjacent its upper end, as indicated at 17, to provide an interior upwardly directed shoulder intermediate its ends. The lower end of the front member 16 has an inwardly extending flange 18, the terminal portion of which is bent back upon itself, as indicated at 19, and then upwardly in spaced relation to the back face 70 of the front member, as indicated at 20, to provide between the back face of the front member and this terminal portion a groove 21, the upper end of which is open. From the upper edge of the front member a rearwardly directed flange 22 extends, the rear end of which is bent downwardly, as indicated at 23. This down-bent portion is less than the distance between the upper end of 75 the front section and the offset 17 for a purpose presently to appear. The lower frame member 14 has a front member 24, the upper end of which is provided with an inwardly directed flange 25, the rear end of which is reverted upon the upper surface of 80 the flange in spaced relation thereto, as indicated at 26, for a purpose presently to appear. The lower end of the front member 24 of the lower frame member is provided with a rearwardly directed flange 27, the terminal portion of which is upwardly bent, as indicated at 28. The side members 15, as stated before, may be of any desired construction. The front members 29 thereof

85 in all instances will preferably be provided at their inner edges with a rearwardly directed flange 30, the rear edge of which is reverted in spaced relation to the flange, 90 as at 31. The back 11 has at its sides, top and bottom rearwardly directed flanges 32, the flange 32 at the bottom engaging between the flange 25 and its reverted portion 26 of the bottom member, while those at the sides engage between the flanges 30 and 105 their reverted portions 31 to limit the rearward movement of the back within the frame. The upper edge of the back has its flange 32 in approximate alignment with the flange 18 of the lower end of the front 110

100

105

110

member 16 of the top frame member. When the back is in position a retaining strip 33 is applied to the upper end of the lower frame member, this retaining strip having 5 at its upper end a horizontally and rearwardly directed flange 34 overlying the flange 25 of the bottom frame member in spaced relation thereto. Adjacent its rear end the flange 34 of the retaining strip is 10 offset downwardly, as at 35, so that its terminal portion 36 lies against the upper surface of the flange 25 and extends slightly into the space between the flange 25 and its reverted portion 26. The free end of this 15 reverted portion 26 is preferably somewhat closer to the flange 25 than the attached end thereof and in the formation of the flange 32 of the lower end of the back member 11 its rear edge is preferably reverted, as indicated at 37, thus increasing the thickness 20 of the flange so that when the rear end of the retaining strip extends beneath the flange of the back member, as it does when in position, this flange is elevated to such 25 a point that it cannot escape from the restricted mouth of the slot in which it is engaged. The offset portion 35 of the retaining strip parallels the back member 11 in spaced relation thereto for a purpose presently to appear.

What we term a cage 38 is provided, this cage being of slightly greater length than the width of the back and consisting of two sheet metal sections 39 and 40, the section 35 39 being hereinafter referred to as the rear section and the section 40 as the forward section of the cage. The forward section of the cage is formed to provide a vertical section 41 which is adapted to enter the groove 40 21, formed by the terminal 20 and front wall 16 of the upper frame member, and is of slightly greater length than the depth of such groove. At the upper end of this vertical section the plate is horizontally bent, 45 as at 42, then vertically bent, as at 43, the upper end of this vertical portion having a horizontal forwardly extending flange 44, the forward edge of which lies in the same plane as the front face of the vertical portion 41 and is separated from the lower end of this vertical portion 41 a distance slightly less than the distance between the offset 17 and the lower end of the front plate 16 of the upper frame member. The rear cage 50 member 39 is formed from a sheet of metal bent to provide a vertical portion 45, the lower end of which is provided with a forwardly directed flange 46 of the same width as the flanges 32 of the back member 11 and 55 designed to receive and support the upper edge flange of this back member. The upper end of this vertical portion is offset, as at 47, the offset section 48 abutting the vertical portion 43 of the front plate 40 and 60 being secured thereto by rivets, as indicated

at 49. The upper end of this offset portion extends above the upper surface of the horizontal flange 44. This cage, being of less length than the distance between the outer side flanges 50 of the side members 15, may 70 be inserted between such side members and the vertical portion 41 engaged in the groove 21 so that the cage is held in position, the flange 46 having first been engaged beneath the upper edge flange 32 of the back 11. 75 One or both of the members have secured thereto at the ends thereof end plates 51, within which are formed openings to receive a shaft 52 which is of greater length than the distance between the end members 80 and preferably but slightly less than the distance between the side flanges 50 of the side frame members 15. The upper end of the offset portion 48 is vertically separated from the lower end of the vertical portion 41 a distance slightly less than the distance from the upper end of the vertical portion 20 and the adjacent section of the flange 22, so that when the upper end of the offset portion 48 is engaged with the flange 22 the 90 lower end of the cage is disengaged from the groove 21.

Upon this shaft, between the end members, are mounted sleeves 52^a in any desired number, each sleeve having secured thereto an arm 53 formed of resilient material and arcuately curved. The sleeve is attached to the arm so that the upper end thereof projects upwardly a distance sufficient to engage against the rear face of the vertical portion 43 of the front cage member 40, so that the movement of the upper end of the arm with the sleeve as a pivot is limited. In this position the lower ends of the arms normally assume a position such as shown in dotted lines in Figure 2 with their ends in spaced relation to the lower end of the back 11. These arms are of such length that they may be moved rearwardly against the back above the surface of the retainer strip 33 and have mounted thereon sliding latches 54, which when moved toward the free end of the arm will engage behind the shoulder formed by the offset 35 of the retainer strip to maintain the lower end of the arm in engagement with the opposed surface of the back member 11. Because of its curvature and resiliency, the portions of the arm intermediate this lower end and the pivot will naturally lie closely against the surface of the back to maintain in position, between themselves and the back, posters or other sheets to be exhibited upon the bulletin board. The shaft, when the cage is removed, may be slid out of the cage and further sleeves 52^a and arms 53 applied thereto as desired. This removal of the cage can only be effected from the rear of the bulletin board which will preferably be secured against some flat surface.

As a means for attaching the bulletin board to such a flat surface, we preferably provide headed retaining members 55 extended into the surface, indicated at 56, and having beneath the heads thereof washers 55^a, a space being left between the washers and the surface 56 so that the upturned flange 28 of the lower frame member 14 may be inserted therebetween. To maintain the upper frame member in position, we employ attaching brackets 57, each consisting of a strip of metal, one end 58 of which is vertically arranged and of a length equal to the distance between the lower face of the upper flange 22 of the upper frame member and the upper face of the offset portion 17 thereof. To the lower edge of this portion is connected a horizontal portion 59 which is of a length equal to the distance between the rear face of the upper portion of the front plate 16 of the upper frame member and the opposed portion of the upper end of the offset 48 of the rear member of the cage. At this point the bracket is offset upwardly, as indicated at 60, so that its upper face abuts the lower end of the downturned terminal 23 of the flange 22 of the upper frame member until it passes beneath this frame member when it is bent sharply upwardly, as at 61, and has formed therein an opening for the reception of a securing element 62 whereby it may be secured to the surface 56. If two of these brackets are employed, as is preferably the case, the brackets are slid into position by engaging them with the upper frame member beyond the ends of the cage and then sliding them toward the center of the upper frame member a desired distance. In this position they cannot escape because of their coaction interfitting with the cage member and upper frame member and will remain in proper position until the securing elements are inserted. To remove the bulletin board it is merely necessary to remove the securing element of one bracket and to slide the bulletin board to one side or the other until the remaining bracket passes the end of the cage when the bulletin board may be removed therefrom as from a hook.

It will be obvious that the structure hereinbefore set forth is capable of a certain range of change and modification without materially departing from the spirit of our invention, and we accordingly do not limit ourselves to such specific structure except as hereinafter claimed.

We claim:

1. In a bulletin board, a frame including upper and lower frame members and a back therefor, the back having at its upper and lower ends rearwardly directed flanges, the lower frame member having a portion beneath which the flange at the lower end of the back engages to prevent upward movement of the back, means carried by the lower

frame member for preventing disengagement of said flange from beneath said portion, a cage engaged with the upper frame member and removable therefrom upon a predetermined movement thereof with relation to the upper frame member and having a portion engaging beneath the flange at the upper end of the back member to prevent downward movement of the back member, and brackets removably engaged with said upper frame member for supporting the bulletin board preventing such predetermined movement of the cage with relation to the upper frame member.

2. In a bulletin board, a frame including upper and lower frame members and a back therefor, the back having at its upper and lower ends rearwardly directed flanges, the lower frame member having a portion beneath which the flange at the lower end of the back engages to prevent upward movement of the back, means carried by the lower frame member for preventing disengagement of said flange from beneath said portion, a cage engaged with the upper frame member and removable therefrom upon a predetermined movement thereof with relation to the upper frame member and having a portion engaging beneath the flange at the upper end of the back member to prevent downward movement of the back member, brackets removably engaged with said upper frame member for supporting the bulletin board preventing such predetermined movement of the cage with relation to the upper frame member, and means carried by said cage engaging the back member to prevent forward movement of the upper end thereof and maintaining in engagement with the back member a bill or the like to be posted.

3. In a bulletin board, a frame including upper and lower frame members and a back therefor, the back having at its upper and lower ends rearwardly directed flanges, the lower frame member having a portion beneath which the flange at the lower end of the back engages to prevent upward movement of the back, means carried by the lower frame member for preventing disengagement of said flange from beneath said portion, a cage engaged with the upper frame member and removable therefrom upon a predetermined movement thereof with relation to the upper frame member and having a portion engaging beneath the flange at the upper end of the back member to prevent downward movement of the back member, brackets removably engaged with said upper frame member for supporting the bulletin board preventing such predetermined movement of the cage with relation to the upper frame member, and means carried by said cage engaging the back member to prevent forward movement of the upper

end thereof and maintaining in engagement with the back member a bill or the like to be posted, comprising a shaft carried by the cage member, sleeves mounted upon said shaft and having arms attached thereto, said arms being arcuately curved and normally engaging against the upper end of the back member only.

4. In a bulletin board, a frame including upper and lower frame members and a back therefor, the back having at its upper and lower ends rearwardly directed flanges, the lower frame member having a portion beneath which the flange at the lower end of the back engages to prevent upward movement of the back, means carried by the lower frame member for preventing disengagement of said flange from beneath said portion, a cage engaged with the upper frame member and removable therefrom upon a predetermined movement thereof with relation to the upper frame member and having a portion engaging beneath the flange at the upper end of the back member to prevent downward movement of the back member, brackets removably engaged with said upper frame member for supporting the bulletin board preventing such predetermined movement of the cage with relation to the upper frame member, means carried by said cage engaging the back member to prevent forward movement of the upper end thereof and maintaining in engagement with the back member a bill or the like to be posted, comprising a shaft carried by the cage member, sleeves mounted upon said shaft and having arms attached thereto, said arms being arcuately curved and normally engaging against the upper end of the back member only, said means for retaining the flange of the lower end of the back member beneath said portion of the lower frame member including a part opposing the back member in spaced relation thereto, and means at the lower ends of the arms and shiftable upon the arms to engage between said portion of said retaining means and the back and to maintain the arm flatly engaged with said back member.

5. In a bulletin board, a frame including upper and lower frame members and a back therefor, the back having at its upper and lower ends rearwardly directed flanges, the lower frame member having a portion beneath which the flange at the lower end of the back engages to prevent upward movement of the back, means carried by the lower frame member for preventing disengagement of said flange from beneath said portion, a cage engaged with the upper frame member and removable therefrom upon a predetermined movement thereof with relation to the upper frame member and having a portion engaging beneath the flange at the upper end of the back mem-

ber to prevent downward movement of the back member, brackets removably engaged with said upper frame member for supporting the bulletin board preventing such predetermined movement of the cage with relation to the upper frame member, and means carried by said cage engaging the back member to prevent forward movement of the upper end thereof and maintaining in engagement with the back member a bill or the like to be posted, comprising a shaft carried by the cage member, sleeves mounted upon said shaft and having arms attached thereto, said arms being arcuately curved and normally engaging against the upper end of the back member only, said sleeves being slidable upon the shaft and removable therefrom when the shaft is removed from the cage, said shaft being removable from the cage when said cage is removed from the upper frame member whereby to permit ready installation of additional sleeves and arms upon the shaft.

6. In a bulletin board, a frame including upper and lower frame members and a back therefor, the back having at its upper and lower ends rearwardly directed flanges, the lower frame member having a portion beneath which the flange at the lower end of the back engages to prevent upward movement of the back, means carried by the lower frame member for preventing disengagement of said flange from beneath said portion, a cage engaged with the upper frame member and removable therefrom upon a predetermined movement thereof with relation to the upper frame member and having a portion engaging beneath the flange at the upper end of the back member to prevent downward movement of the back member, a shaft mounted within the cage and extending transversely of the frame, and means carried by the shaft and depending therefrom engaging the upper end of the back member to prevent forward movement thereof and positionable against the front surface of the back member to maintain in engagement with the back member a bill or the like to be posted.

7. In a bulletin board, a frame including upper and lower frame members and a back therefor, the back having at its upper and lower ends rearwardly directed flanges, the lower frame member having a portion beneath which the flange at the lower end of the back engages to prevent upward movement of the back, means carried by the lower frame member for preventing disengagement of said flange from beneath said portion, a cage engaged with the upper frame member and removable therefrom upon a predetermined movement thereof with relation to the upper frame member and having a portion engaging beneath the flange at the upper end of the back member to pre-

vent downward movement of the back member, a shaft mounted within the cage and extending transversely of the frame, and means carried by the shaft and depending therefrom engaging the upper end of the back member to prevent forward movement thereof and positionable against the front surface of the back member to maintain in engagement with the back member a bill or the like to be posted, comprising arms rotatably and longitudinally shiftable upon said shaft, said shaft being removable from said cage when said cage is removed to permit the removal or addition of arms thereto.

8. In a bulletin board, a frame including upper and lower frame members and a back therefor, the back having at its upper and lower ends rearwardly directed flanges, the lower frame member having a portion beneath which the flange at the lower end of the back engages to prevent upward movement of the back, means carried by the lower frame member for preventing disengagement of said flange from beneath said portion, a cage engaged with the upper frame member and removable therefrom upon a predetermined movement thereof with re-

lation to the upper frame member and having a portion engaging beneath the flange at the upper end of the back member to prevent downward movement of the back member, a shaft mounted within the cage and extending transversely of the frame, means carried by the shaft and depending therefrom engaging the upper end of the back member to prevent forward movement thereof and positionable against the front surface of the back member to maintain in engagement with the back member a bill or the like to be posted, said arms being arcuately curved and having their lower ends disposed in advance of the back member, the arms being formed of resilient material to permit engagement of such lower ends with the back member, and means carried by said arms and operatively engageable with the lower frame member to maintain the lower ends of said arms in engagement with the back.

In testimony whereof we hereunto affix our signatures.

WILLIAM C. ACHTERKIRCH.
ERNEST B. MARSH.
